FACE MASK

Benjamin Cooper, Woodmere, N. Y.

Application February 27, 1958, Serial No. 49,829

Term of patent 7 years

(Cl. D34—15)

Fig. 1 is a front elevational view of a face mask showing my new design, the dominant features of which reside in the portions shown in full lines.

Fig. 2 is a side elevational view.

The fragmentary portion of a head shown in broken lines is for illustrative purposes only.

I claim:

The ornamental design for a face mask, as shown and described.
